US0D1097769S

(12) United States Design Patent (10) Patent No.: US D1,097,769 S
(45) Date of Patent: * Oct. 14, 2025

(54) FOLDING KNIFE

(71) Applicant: Fiskars Brands, Inc., Middleton, WI (US)

(72) Inventors: Joshua Harris, Sandy, OR (US); Patrick Hunt, Tigard, OR (US)

(73) Assignee: FISKARS BRANDS, INC., Middleton, WI (US)

() Term: 15 Years

(21) Appl. No.: 29/927,615

(22) Filed: Feb. 5, 2024

(51) LOC (15) Cl. 08-03

(52) U.S. Cl.

USPC D8/99

(58) Field of Classification Search

USPC D8/14, 98, 99, 100, 105; D22/118
CPC B26B 1/00; B26B 1/02; B26B 1/04; B26B 1/08; B26B 1/10; B26B 1/042; B26B 1/046; B26B 1/048; B26B 3/06; B26B 3/08; B26B 5/00; B26B 5/001; B26B 5/003; B26B 5/005; B26B 5/006; B26B 11/00
